UNITED STATES PATENT OFFICE

2,604,578

DETACHABLE LIGHT HOUSING FOR
SUCTION CLEANEROtis B. Sutton, Canton, Ohio, assignor to The
Hoover Company, North Canton, Ohio, a cor-
poration of Ohio

Application January 16, 1948, Serial No. 2,708

8 Claims. (Cl. 240—2)

1

This invention relates to suction cleaners, and more particularly to an electric lighting device or headlight construction for an electrically operated portable, domestic household suction cleaner of a type employing a substantially horizontally disposed motor having a suction nozzle, a fan case and a motor housing arranged one behind the other in the order named.

The suction cleaner is equipped with a lighting device for illuminating floor areas, dark corners and places underneath articles of furniture in order that the cleaner nozzle may be more readily, quickly and easily manipulated for cleaning areas otherwise poorly illuminated.

It is an object of the present invention to provide wheel supported type suction cleaner with a dirt-finder light construction in which hazards resulting from loose electrical connections or short circuiting are eliminated.

Still another object of the invention is the provision of a converter cover plate adapted for mounting the electrical connections therefor for the dirt-finder light construction in which the electrical connections are suitably insulated one from the other by laminates formed from layers of paper or cloth impregnated with thermosetting and/or thermo-plastic material.

It is a further object of the present invention to provide an electrically-operated wheel supported type suction cleaner with a dirt-finder light construction that may be readily attached and detached from the cleaner in the limited space, usually available in various types of portable suction cleaners.

Another object of the invention is to provide a converter cover plate in which the electrical leads are molded as inserts in the converter cover and act as the converter cover holding means as well as electrical conductors for the dirt-finder lamp.

Furthermore, it is an object of the invention to provide a dirt-finder light attachment for a suction cleaner having relatively few parts of simple and inexpensive construction and manufacture, assembly and use.

Referring now to the drawings in which a preferred embodiment of the present invention is disclosed, and in which the same reference character refers to the same parts throughout:

Figure 1 is a front view of a suction cleaner embodying the dirt-finder cover plate of the present invention;

Figure 2 is an enlarged longitudinal sectional elevation of the improved dirt-finder cover plate shown in Figure 1, and attached to a fragmentary portion of a suction cleaner;

2

Figure 3 is a plan view of the dirt-finder cover plate of this invention as detached from the suction cleaner; and,

Figure 4 is a vertical sectional view taken along line 4—4 of Figure 3, looking in the direction of the arrows, illustrating the method of affixing the strip inserts forming the electric leads between the sheets of laminate for positioning and insulating the electrical conductors in a finished molded cover plate.

In the form of the invention as illustrated in Figures 1 and 2, there is shown a suction cleaner having its operating motor disposed substantially upon a horizontal axis and enclosed within a motor housing 10, forwardly of which there is provided a fan housing 11 in communication with a suction nozzle 12, the working mouth of which is indicated at 13. The aforesaid elements constitute the casing of the cleaner and they are supported upon front and rear wheels 14 and 15. The usual type of agitator 16 which may include brush and/or beater elements is driven through a belt 17 from a pulley 18 on an extension 19 of the motor-fan shaft which extends through the fan-eye to which a converter for the dusting tools for the suction cleaner is readily attached upon the removal of the dirt-finder cover plate and/or converter cover 20 of this invention. It is preferred to form the motor housing 10 of a suitable molded plastic material as well as the nozzle and fan housing construction of a suction cleaner although it is within the scope of the invention that the various parts of the housing or certain parts thereof may be either formed of molded plastic material or metal.

The nozzle 12 is preferably provided with a converter opening 21 having an upstanding supporting bracket 22 formed at the lower edge of the converter opening 21, as illustrated in Figure 2. Suitably affixed to rear face of the supporting bracket 22 at the upper edge thereof there is a resilient latch member 23 which is engaged by a complementally formed latch member 24 affixed to the cover plate 20 by securing means 25. Depending flanges 26 and 27 complete the formation of the converter cover plate 20 and suitable sealing means may be provided between the lower edges of the flanges 26 and 27 and the outer periphery of the opening 21 to provide an effective seal as is well understood in the art to prevent excess leakage of air about the edges of the converter opening contiguous to the converter cover plate 20 which would tend to reduce the efficiency of the suction cleaner.

A reflector construction 28 for a dirt-finder light source 29 is provided by a curved surface

39 formed by the lower front face of the up-standing supporting bracket 22, as illustrated in Figure 2. The upper portion of the reflector construction is formed by a curved surface 31 formed on the lower front edge of the cover plate 20. The lower front edge of the cover plate 20 which forms a reflector surface 31 is complementally formed with respect to the upper edge of the supporting bracket 22, as illustrated in Figure 2, and the complementally formed edges thereof may be sealed in a suitable manner to prevent leakage of air within the suction nozzle 12 which would tend to reduce the efficiency of the cleaner. The reflecting surfaces 30 and 31 form substantially a parabolic surface in cross section, as illustrated in Figure 2, with the dirt-finder light source 29 mounted at the focus thereof in order to project an intense beam of light forwardly and downwardly ahead of the suction cleaner nozzle and laterally across the entire length thereof. The curved surfaces 30 and 31 forming the reflector may be suitably coated with a reflective surface to improve the reflection of light therefrom.

The dirt-finder light source 29 is preferably a conventional appliance bulb adapted to operate from the electrical circuit of the suction cleaner, usually 110 volts A. C. or D. C., although it is within the scope of the invention that lower voltage appliance bulbs may be utilized, the lower voltage for the energization thereof being obtained by tapping leads from the field coils of the suction cleaner motor.

An appliance bulb 29 is adapted for detachably mounting in a socket 32 affixed to the depending flange 26 contiguous to the side of the reflecting chamber 28. Although the socket has been illustrated as being affixed to the left flange 26, the socket 32 may be obviously mounted upon the other flange. The socket 32 may be either of the bayonet type or screw type for receiving a complementally formed base of the appliance bulb.

Referring particularly to Figures 2 and 3, there will now be described a preferred construction for integrally molding electrical leads 33 and 34 within molded cover plate 20. The electrical leads 33 and 34, metal strips for example, as illustrated in Figures 2 and 3, are embedded in the cover plate 20. The lower ends of the leads 33 and 34 are adapted to receive securing means 35 for affixing pig-tail leads 36 and 37 which are affixed to connections on the socket 32 for completing the electrical circuit to appliance bulb 29. The upper ends of the leads 33 and 34 extend rearwardly, as illustrated in Figures 2 and 3, as prongs 38 and 39 extending through slots 40 formed in the front wall of the motor housing 10. As previously described, it is preferred to form the housing 10 from a suitably molded plastic material which serves as an insulator between the conductors 33 and 34, but, however, it is within the scope of the invention, if the housing 10 should be formed of a molded metal, that suitable insulation may be provided at the slots 40 and contiguous thereto, without departing from the scope of the invention, to suitably insulate the prongs 38 and 39 at this point. The prongs 38 and 39 of the leads 33 and 34 engage resilient complementally formed connections 41 which are affixed to the housing 10 by securing means 42 which serve to connect leads 43 thereto, the leads 43 preferably being connected in parallel to the 110 volt electrical circuit for the suction cleaner motor.

Referring to Figures 2 to 4 inclusive, there will now be described the novel method of integrally molding the metal strips 33 and 34 in the molded plastic converter cover plate 20. Prior to this invention, it has been extremely difficult to mold metal inserts which particularly serve as electrical conductors within a relatively thin section of molded material. In the past when electrical conductors of this nature have been molded within a thin walled section of plastic material, they tended to show through because it is difficult to position the inserts within the mold and to place the molding powder uniformly about the metal inserts. For insulation between the inserts 33 and 34, it is preferred to use a form of laminate which is a paper laminate impregnated with a thermo-setting plastic such as a phenol condensation product. Although it is preferred to use a type of paper impregnated laminate, it is within the scope of the invention that any type of laminate having suitable insulating qualities may be utilized. For example, laminates may also be used made from urea formaldehyde and melamine formaldehyde plastic. Normally laminates are made by impregnating layers of paper or cloth with a thermo-setting plastic material. Although it is preferred to use a laminate impregnated with a thermo-setting plastic material, it is also within the scope of the invention that laminates fabricated from paper or cloth and impregnated with a thermoplastic material having suitable insulating qualities may also be utilized.

It is therefore preferred to utilize prefabricated sheets of an impregnated paper laminate complementally formed as illustrated at 44 and 45 extending substantially the width of the converter cover plate 20 as illustrated in Figure 4 and extending substantially the length thereof as illustrated in Figure 2. The laminates 44 and 45 may also be formed with complementally formed grooves 46 and 47 adapted to receive the inserts 33 and 34. The grooves 46 and 47 may be formed in the laminates 44 and 45 after the members have been cut from sheet material and/or strip material at the same time as these members 44 and 45 are formed to the shape as illustrated in Figure 2 of the converter cover plate 20 within a suitable mold under heat and pressure sufficient to mold the members 44 and 45 to shape depending upon the type of thermo-setting and/or thermo-plastic material used in fabricating the laminate. It is preferred to form the inserts 33 and 34 respectively with the holes 48. The upper and lower members 44 and 45 at the time of forming may also be provided with complementally formed dimples, as illustrated in Figure 4, complementally formed with respect to the holes 48 in the inserts 33 and 34 for locating the curved metal inserts with respect to the finished converter cover 20. The laminates 44 and 45 may be heat fused together at the point where the complementally formed dimples engage the holes 48 of the inserts securely affixing the laminates 44 and 45 together and likewise affixing the metal inserts in their correctly located position between the laminates.

The prefabricated laminates comprising the members 44 and 45 together with the metal inserts 33 and 34 which have been prefabricated to substantially the final shape of the molded plastic cover plate 20 may then be placed within the mold for completing the molding of the plastic cover plate 20. Suitable molding powder either of thermo-setting and/or thermo-plastic material may be placed in the lower half of the mold

whereupon the fabricated laminate may be located and sufficient molding powder placed thereover to complete the molding of the thermo-plastic cover upon the closing of the mold and the application of heat and pressure sufficient for completing the molding of the plastic cover plate 20 depending upon the type of thermo-plastic and/or thermo-setting molding powder being used for the cover plate and the formation of the laminate therefor. Upon the completion of the molding operation, the molded plastic cover plate 20 is complete in its horizontal portion and depending flanges thereon and the metal inserts which in the preferred form of the invention serve as conductors are integrally molded together.

In addition to the above method of molding the dirt-finder cover plate, it is within the scope of the invention as another embodiment thereof to utilize in place of the molding powder as described above pre-formed laminates containing a high percentage of thermo-setting and/or thermo-plastic material. The high percentage of thermo-plastic and/or thermo-setting material imparts a good flow and forming characteristic in the fabrication of the dirt-finder cover plate. In using this method of fabrication, the pre-fabricated laminates comprising the members 44 and 45 together with the metal inserts 33 and 34 are formed as disclosed above. Then, suitably pre-formed laminated material similar to the laminates used in forming the members 44 and 45 and containing a high percentage of plastic material are pre-formed to substantially the shape of the lower and upper parts of the completed dirt-finder cover plate construction and complementary to the members 44 and 45. These complementally formed pre-forms are adapted to be inserted in the mold for completing the molding operation. The integrally molded laminates together with the metal inserts thereof are placed in position upon a lower preform positioned within the mold and the upper pre-form of plastic laminated material is placed upon the integrally molded laminates 44 and 45 and the molding of the thermo-plastic cover plate is completed upon closing of the mold and the application of heat and pressure sufficient for completing the molding of the plastic cover plate, depending upon the type of thermo-plastic and/or thermo-setting pre-formed laminates used for the cover plate and the formation of the fabricated laminates therefor. Upon the completion of the molding operation, the molded plastic cover plate 20 is complete with its horizontal portion and depending flanges together with the metal inserts therefor as previously described.

It is thus evident that there has been formed by the above methods a dirt-finder cover plate formed from molded plastic material having a thin cross-section which is effectively reinforced and strengthened by the integrally molded laminate formed therein together with metal inserts therefor which in the preferred embodiment of the invention serve as conductors for a dirt-finder light source mounted thereon.

It is evident that a preferred embodiment of the dirt-finder cover plate construction has been disclosed with reference to a dirt-finder light construction and the mounting of the electrical conductors therefor for connecting the dirt-finder light source with a source of electrical energy at a distance therefrom by the shortest most direct route possible without leading the conductors through the fan chamber and/or the suction nozzle or in a roundabout manner from the motor

housing underneath the bumper for the suction cleaner. This construction is likewise adaptable for molding, for example, a reinforced converter cover plate in which the conducting prongs 38 and 39 of the preferred embodiment serve solely as latching prongs engaging complementally formed slots for mounting the cover plate on the suction cleaner, the extensions of the prongs, for example the inserts 33 and 34, serving to reinforce the cover plate as previously described together with the laminates between which the metal inserts 33 and 34 are positioned and affixed. A reinforced cover plate formed in this manner is provided with reinforced extending prongs and the like which prevent breaking off of the prongs and also prevents the cover plate from warping.

In order to affix the cover plate 20 comprising the integrally molded conductors 33 and 34 for the dirt-finder light source 29, the prongs 38 and 39 are positioned within the complementally formed slots 40 engaging the resilient connections and/or spring clips 41. The cover plate 20 with the dirt-finder light 29 mounted thereon is then tilted downwardly with the complementally formed latch portion 24 thereon engaging the latch member 23 securely affixing the cover plate in position. The cover plate 20 is removed in the reverse order by lifting up on the lower portion of the cover plate unlatching the latches 23 and 24 after which the prongs 38 and 39 may be withdrawn disconnecting the electrical circuit of the cover plate from the electrical circuit formed by the connections 43 which are connected to the electrical circuit of the suction cleaner and energized thereby. In the detached position of the cover plate 20, the converter for the suction cleaner may be positioned within the fan-eye of the fan chamber and affixed thereto after the driving belt 17 has been detached. It is also necessary to detach the cover plate 20 in repairing and replacing the driving belt 17. The appliance bulb 29 may be either placed or assembled on the cover plate 20 with the cover plate in the attached position, or the appliance bulb may be applied to the dirt-finder cover plate by detaching and attaching the cover plate as previously described. As in all modern suction cleaners, a suitable bumper construction 50 is provided which serves to protect the dirt-finder cover plate of the invention.

Although the molded cover plate 20 has been described by first prefabricating the laminates 44 and 45 and assembling the inserts 33 and 34 and affixing them thereto as previously disclosed above, it is also within the scope of the invention that the preformed laminates and the metal inserts together with the molding powder may be assembled in the mold for completing the cover plate without first forming a prefabricated member including the upper and lower laminates 44 and 45 and the inserts 33 and 34 assembled and affixed together. The preferred methods of fabricating the cover plate as disclosed with reference to Figure 4 also prevents the laminates from setting up before the molding powder is poured in or the pre-forms of plastic laminates inserted within the mold and greatly reduces the time of fabrication, for example, as is necessary to separately position each part in the mold during the molding operation.

It is thus evident that there has been disclosed an improved dirt-finder cover plate construction which provides a lighting device and a cover plate for a converter opening for a suction cleaner

which is very simplified in design, and easy to assemble. It also enables the dirt-finder light construction to be affixed to the cleaner in a relatively small and limited space with a suitable socket for the appliance bulb and electrical conductors mounted on the cover plate and insulated therefrom which provides the shortest possible electrical connection necessary from the electrical circuit of the motor for the suction cleaner to the dirt-finder light construction located there as close as possible to the surface over which the suction cleaner passes in the cleaning operation to efficiently illuminate and project a beam of light forwardly and downwardly upon the surface undergoing cleaning.

What is claimed is:

1. In a suction cleaner, a casing including a fan housing and a nozzle, said casing being formed with a converter opening in the front portion thereof, a cover plate construction formed of molded insulating material adapted to be attached to and detached from said casing for opening and closing said converter opening, a dirt-finder light source mounted on the lower end of said cover plate, a pair of electrical conductors embedded in said cover plate each having a portion projecting beyond the upper end of said cover plate, means electrically connecting said conductors to said light source, a pair of openings in said casing positioned to receive the projecting portions of said electrical conductors to aid in holding said cover plate in position to close said converter opening, and a pair of electrical contacts in said casing positioned to engage the projecting portions of said conductors when inserted into said openings in said casing.

2. In a suction cleaner construction comprising a casing including a fan housing, a nozzle having a converter opening therein, and a motor housing and further including an electrical circuit for energizing the suction cleaner, a dirt-finder cover plate construction comprising a thin-walled molded plastic converter plate adapted to serve as a closure for the converter opening, a dirt-finder light source positioned at the lower end of the cover plate contiguous to the converter opening and contiguous to the surface over which the suction cleaner is propelled, the dirt-finder light source adapted to project a beam of light forwardly and downwardly ahead of the nozzle and laterally thereof, a reflector formed by a curved portion of the cover plate and a symmetrically formed curved portion formed on the suction cleaner nozzle contiguous to the lower edge of the converter opening whereby a reflector is formed in the mounted position of the dirt-finder cover plate upon the converter opening, metal inserts adapted to form electrical connections adapted to be connected to the dirt-finder light source and to the electrical circuit of the suction cleaner, means for insulating the metal inserts and integrally molded with the inserts within the cover plate whereby the conductors are insulated and the cover plate reinforced, and complementally formed means formed on the metal inserts and the electrical circuit of the suction cleaner whereby in the mounted position of the dirt-finder cover plate the electrical circuit of the dirt-finder light source is completed and in the detached position of the cover plate the electrical circuit of the dirt-finder light source is open.

3. The combination with a suction cleaner comprising a nozzle and a converter opening formed therein, a fan chamber formed to the rear of the

nozzle and a motor housing positioned rearwardly and contiguous to the fan chamber, of a molded dirt-finder cover plate construction adapted to be mounted on the converter opening, a dirt-finder light source operatively mounted upon the lower edge of the cover plate and contiguous to the converter opening, a reflecting surface formed by the lower portion of the dirt-finder cover plate and a contiguous surface in the lower edge of the converter opening in the closed position of the cover plate, an electrical circuit for the dirt-finder light source comprising a plurality of metal inserts integrally molded in the confines of the cover plate and extending substantially the length thereof whereby the molded cover plate is adapted to insulate the metal inserts, and complementally formed means formed on the metal inserts and on the housing for the motor adapted to serve as cover holding means as well as electrical conductors for the dirt-finder light source whereby, in the attached position of the dirt-finder cover plate, the electrical circuit of the dirt-finder light source is completed and in the detached position of the dirt-finder light source, the electrical circuit thereof is open.

4. As an article of manufacture, a dirt-finder cover plate for a converter opening of a suction cleaner comprising a body of plastic material encompassing a plurality of reinforcing sheets of fibrous material impregnated with plastic material, a lamp socket carried by said body, and metal inserts forming an electrical circuit for said socket lying within said body between certain of said sheets and having portions thereof connected to said lamp socket and other portions thereof extending from an edge of said cover plate to form electrical connecting prongs on said cover plate.

5. As an article of manufacture a dirt-finder cover plate adapted to be attached to and detached from a converter opening in a suction cleaner, said cover plate comprising a body portion consisting of a plurality of superposed sheets of fibrous material, a pair of metal inserts lying between certain of said sheets and projecting outwardly of one edge thereof, a plastic material bonding said sheets and metal inserts into a unitary structure, a lamp socket secured to a portion of said plate remote from the projecting portions of said inserts, means for electrically connecting said socket to said inserts, said inserts reinforcing said plate and forming an electrical circuit to said socket, the projecting portions of said inserts forming fastening means for said cover plate, and additional latching means on said cover plate to aid in securing said plate to a suction cleaner.

6. In a suction cleaner, a casing including a fan housing and nozzle, a converter opening formed in the nozzle, a cover plate for closing said converter opening, a lamp carried by said cover plate in position to illuminate a surface area in front of said nozzle, a pair of electrical conductors connected to said lamp and embedded in said cover plate, said conductors projecting outwardly of the upper edge of said cover plate and extending into complementary insulated recesses in said casing to aid in securing said cover plate on said casing, and electrical contacts in said casing engaging the projecting portions of said conductors.

7. In a suction cleaner of the type having a motor casing, a fan chamber positioned forwardly of the motor casing, a suction nozzle structure extending forward of the fan chamber and a

converter opening in the nozzle structure providing access to the suction inlet of the fan chamber, the combination of a cover plate structure for said converter opening comprising a body of electrically insulating material lying over said opening and having a portion extending over said fan chamber into engagement with said motor casing, a dirt finder lamp mounted on said cover plate in position to illuminate the surface area ahead of said nozzle, metallic strips embedded in said cover plate and projecting outwardly of the portion thereof engaging said motor casing, said motor casing having openings receiving the projecting portions of said strips, electrical contacts in said motor casing engaging the projecting portions of said strips, and means electrically connecting said lamp to said strips.

8. In a suction cleaner of the type having a motor casing, a fan chamber positioned forwardly of the motor casing, a suction nozzle structure extending forwardly of the fan chamber and a converter opening in the nozzle structure providing access to the suction inlet of the fan chamber, the combination of a cover plate structure for said converter opening comprising a body of electrically insulating material lying over said opening and having a portion extending over said fan chamber into engagement with said motor casing, a dirt finder lamp mounted on said cover plate in position to illuminate the surface area ahead of said nozzle, a light reflecting structure for directing the light from said lamp in a desired direction formed partly on said cover plate and partly on said nozzle, metallic strips embedded in said cover plate and projecting out-

wardly of the portion thereof engaging said motor casing, said motor casing having openings receiving the projecting portions of said strips, electrical contacts in said motor casing engaging the projecting portions of said strips, and means electrically connecting said lamp to said strips.
